UNITED STATES PATENT OFFICE.

KARL ERIK WILHELM JAGDMANN, OF STOCKHOLM, SWEDEN.

MEANS FOR APPLYING MORTAR TO HOLLOW BRICKS.

Original application filed June 25, 1920, Serial No. 391,738, and in Sweden August 2, 1918. Divided and this application filed June 30, 1921. Serial No. 481,703.

This invention relates to a method of applying mortar to hollow bricks in an even and thin layer, divided from my copending U. S. patent application Serial No. 391,738.

5 The known method of applying the mortar, when erecting walls and floorings from hollow bricks, consisting in dipping the bricks into the mortar has proved to be very unsatisfactory, because of the joints not being entirely filled. In walls built up from hollow bricks by dipping the bricks into the mortar, the joints will not be tight owing to the mortar covering the joint surfaces only at intervals. The significance thereof with 10 reference to the strength as well as to the insulation can easily be seen, and in case of floorings of the type described in my application Serial Number 391,738 such a method is simply detrimental, since the whole joint 15 surface of the bricks is required to resist the great stresses exerted on the bricks. The difficulties in this case are very great since the joints, especially the vertical joints in floorings of said type, should be very thin 20 in order to resist the enormous stresses arising on account of the tightening of the rows of bricks and the immediate removal of the scaffolding without allowing the flooring to settle even in the slightest degree.

25 Attempts have been made to apply the mortar to hollow bricks by spreading the mortar by means of a pencil, but this has also resulted in an incomplete contact of the joint surfaces. To apply a great quantity 30 of mortar to hollow bricks in walls or floorings in the same manner as in case of common solid bricks is also inconvenient, since the surplus of the mortar in such case will flow down into the cavities of the bricks, all 35 the more as relatively thin mortar must be used.

The object of this invention is to remove said inconveniences by spreading the mortar across the surface to be coated by means 40 of an implement so constructed as to apply the mortar in a thin layer of uniform thickness only on the surfaces to be covered with mortar.

To obtain this result any implement may 45 be used, preferably, however, such one consisting of a plane plate or the like provided at one or more edges with two or more projections or teeth.

Several embodiments of an implement adapted to carry the method into practice 55 are illustrated in the accompanying drawing in which:

Fig. 1 shows the implement in combination with a support or box for the brick.

Fig. 2 is a plan view of said support or 60 box; and,

Fig. 3 is a section on line G—H in Fig. 2.

In order that the brick when coated with the mortar shall be quite regular, that is to say, that its opposite surfaces shall be parallel and its angles right, even if the stone in itself be somewhat irregular, a device is provided which is adapted for use in connection with the implement or trowel. Said device may consist of a support for the brick, 65 said support being provided with guides for guiding the brick, the upper edge of the guides projecting so far beyond the surface in question as corresponds to the thickness 70 of the coating of mortar.

Referring to the drawing in detail said support consists of a box 7 in which the brick 12 is placed and supported by supports 8. The upper edges of the guides or guiding ribs 9 lie in a plane a distance above 75 the top of the brick corresponding to the thickness of the layer of mortar. Said guiding ribs may also be placed outside the box or on another level, provided that the trowel 80 1st be constructed for that purpose. The apparatus is preferably placed in relation to the mortar container 5 as shown in Fig. 1, the surplus of the mortar falling down in the same. Preferably the apparatus is somewhat inclined. It may be made of wood or 85 iron or other material.

The cavity of the bricks is filled with a core 10, the upper edge of which is on a level with the guiding ribs 9, and by means thereof the mortar is prevented from falling 90 down into the cavity. The guiding ribs 9 and the walls of the box 7 prevent the mortar from falling down onto the outer sides of the brick and soiling the same.

The apparatus shown in the drawing is 100 without movable parts, and the brick may be laid down directly into the box. If the bricks are very heavy or relatively high or if from other reasons it will be difficult to lay them down into the box, either the supports 8 may be constructed so as to be able 105

to be raised or lowered, the brick thereby being raised or lowered, or the box and the core may be raised and lowered in relation to the brick. The apparatus may also be 6 slid onto or shut over the brick.

This apparatus affords among other things the advantage that it requires less skillfulness in use, it being less difficult to apply the mortar on a top surface than on a more or 10 less downwardly inclined surface.

The manner of operation of the implement will, it is thought, be easily understood from the above description and therefore further description is deemed unnecessary.

15 What I claim as new and desire to secure by Letters Patent of the United States is:—

1. An apparatus to be used in applying mortar to hollow bricks by means of a trowel adapted to be moved across the surface to be covered with mortar before laying a brick, comprising a box constituting a support for the brick and having portions of the walls thereof disposed above the brick to form guides for the trowel when moving 20 across said surface, and cores in said box arranged to fill the hollow of the brick and prevent mortar from falling through the cavities of the brick during application of mortar thereto.

3. An apparatus to be used in applying mortar to hollow bricks by means of a trowel adapted to be moved across the surface to be covered with mortar before laying a brick, comprising a box adapted to support the brick, the side walls of the parts constituting guides for the trowel when moving 35 across the said surface, and bearing surfaces in said box for the brick adapted to be raised and lowered.

4. An apparatus to be used in applying mortar to hollow bricks by means of a trowel adapted to be moved across the surface to be covered with mortar before laying a brick, comprising a box constituting a support for the brick, the walls of the box constituting guides for the trowel when moving 45 across said surface, and cores in said box arranged to fill the hollow of the brick and prevent mortar from falling through the cavities of the brick during application of mortar thereto, said core being movable with respect to the brick located in said box.

5. An apparatus to be used in applying mortar to hollow bricks by means of a trowel adapted to be moved across the surface to be covered with mortar before laying a brick, comprising a support for the brick and guides carried by said support for directing the movement of the trowel across 55 said surface.

6. An apparatus to be used in applying mortar to hollow bricks by means of a trowel adapted to be moved across the surface to be covered with mortar before laying a brick,

comprising a support for the brick, portions 65 of said support constituting guides for the trowel when moving across said surface, said support including movable and stationary members arranged to support the brick, the movable members being capable 70 of being lowered beneath the bearing surface of the stationary members and the brick supported upon said stationary members.

6. An apparatus to be used in applying 75 mortar to hollow bricks by means of a trowel adapted to be moved across the surface to be covered with mortar before laying a brick comprising a support for the brick forming guides for the trowel when moving 80 across said surface, the bearing surface of said support being parallel with said guides, in order that the brick when coated with the mortar will have its opposite surfaces parallel, even if the brick in itself be somewhat 85 irregular.

7. An apparatus to be used in applying 90 mortar to hollow bricks by means of a trowel adapted to be moved across the surface to be covered with mortar before laying a brick, comprising a box constituting a support for the brick and having the walls thereof arranged to form guides for the trowel when moving 95 across said surface, and cores in said box arranged to fill the hollow of the brick and prevent mortar from falling through the cavities of the brick during application of mortar thereto, the bearing surface of said support being parallel with said guides.

8. An apparatus to be used in applying 100 mortar to hollow bricks by means of a trowel adapted to be moved across the surface to be covered with mortar before laying a brick, comprising a box adapted to support the brick the side walls of said box constituting guides for the trowel when moving 105 across the said surface, and bearing surfaces in said box for the brick adapted to be raised and lowered, said bearing surfaces being located in a plane parallel with said guides.

9. An apparatus to be used in applying 110 mortar to hollow bricks by means of a trowel adapted to be moved across the surface to be covered with mortar before laying a brick, comprising a support for the brick forming guides for the trowel when moving across said surface, said support including movable and stationary members arranged to support the brick, the movable members being capable of being lowered beneath the bearing surface of the stationary members and the brick supported upon said stationary members, the bearing surfaces of said movable and stationary members being 115 located in planes parallel with said guides.

In testimony whereof I affix my signature.

KARL ERIK WILHELM JAGDMANN.
